RAIL BOND TERMINAL

North C. Shaver, Johnstown, Pa., assignor to
 Penn Machine Company, Johnstown, Pa., a
 corporation of Pennsylvania

Application October 5, 1934, Serial No. 746,963

4 Claims. (Cl. 173—278)

In modern railway track construction the ends of aligned rails are electrically bonded together.

In standard steam railway practise the bond is usually located above the rail bases, the cable being frequently protected against injury by the fish plate which bridges the rail ends. The relatively close spacing of the cross ties renders the positioning of the bond beneath the rail bases impractical.

10 However, in light railway construction, such as for instance in mines, where the cross-ties or rail supports generally are spaced farther apart and where derailments are relatively frequent so that an exposed bond is liable to injury by contact with the wheel flanges, it is considered preferable to install the rail bonds beneath the bases of the rails so that the latter will protect the bonds from injury.

It is the present practise among manufacturers 20 of rail bonds to provide different types of bonds for installation above the rail bases and beneath the rail bases, respectively, and thus a rail bond designed to be installed above the rail bases cannot be installed beneath the latter, and vice versa.

25 An important object of the present invention is the provision of a reversible rail bond which may be installed either above or beneath the rail bases with equal facility and which will be efficient in either position.

30 Another object which I have in view is the provision of a better degree of conductivity between the rails and the copper cable which forms the intermediate portion or body of the rail bond.

Other objects will be apparent from the following description.

The first mentioned object I attain by means 40 of the novel structure and shape of the terminals of my improved bond, such terminals being so designed that in either position, to locate the cable either above or beneath the rail bases, a satisfactory electrical connection with the rail base is provided and furthermore, sufficient provision is made for the proper welding of the terminal to the rail base. By means of my improved terminals I get a much better electrical connection between the bond and the rails.

The second mentioned object I also attain by butt-welding the end of the cable to the terminals so that there is good electrical conduction 50 between the rails and the cable.

Other novel features of construction, and also of arrangement of parts, will appear from the following description:

55 In the accompanying drawing, wherein I have

illustrated a practical embodiment of the principles of my invention,

Fig. 1 is a perspective showing the rail bond installed above the bases of two aligned rails.

Fig. 2 is a similar view showing my rail bond 5 reversed and located beneath the rail bases.

Fig. 3 is a sectional view taken along the line 3—3 in Fig. 1.

Fig. 4 is a detail in longitudinal section showing the connection of the end of the cable to the terminal.

Fig. 5 is a perspective of one sleeve blank which is bent up and clamped about the end of the cable before butt-welding the cable to the end of the terminal, the view also illustrating in dotted lines 15 the bent-up sleeve clamped on the end of the conductor.

Referring to the drawing, 1 and 2 represent aligned rails whose ends abut and are to be electrically bonded. 3 represents the fish plates 20 which connect the rail ends together and are bolted in place through the webs of the rails.

The rail bond comprises the intermediate flexible conductor 4, usually of copper, and in the form of a plurality of helically wound wire 25 strands.

The ends of the conductor 4 are electrically and mechanically connected to the two terminals 5 by means of which the bond is installed to electrically bridge the rail joint. These terminals 30 may be made of any suitable metal having the requisite conductivity, but I prefer to use for this purpose castings formed of malleable steel.

The structure of these terminals is of the utmost importance, as I so construct them that they 35 may be mounted on the base of the rail as shown in Fig. 1, or they may be reversed and mounted as shown in Fig. 2 with the same efficient results and with the same facility.

The body of the terminals is composed of two 40 outwardly converging wings or sides 6 and 7 which merge at their inner side edges into the arcuate bridge portion 8. The cross section of the body of the terminal is substantially U-shaped with two diverging sides which are symmetrical in respect to a plane bisecting their included angle. The inner faces of these wings are plane and their outward divergence is at the proper angle so that they may be wedged by 45 driving onto the edge of the rail base either in the disposal shown in Fig. 1, or that shown in Fig. 2. By providing the proper angle between the terminal wings, the bond may be preliminarily installed on the rail bases in proper po- 55

sition and will hold its position while the welding is accomplished.

The outer side edges 9 of the wings 6 and 7 are substantially straight lines as are also the 5 outer end edges 10 of said wings. The outer edges 9 may be used for welding the terminal to the flange of the rail longitudinally of the latter. The edges 9 and 10 are preferably disposed at substantially right angles to each other.

10 The terminals, with the ends of the conductor 4 connected thereto, are first wedged on the rail, either as shown in Fig. 1, or reversed as shown in Fig. 2, and then the edges 9 and 10 of the uppermost wing, shown as 6 in Fig. 1, and as 7 in 15 Fig. 2, are welded to the upper surface of the rail base throughout substantially their full lengths, thus not only firmly and rigidly attaching the terminals to the rail bases but also effecting a union which provides efficient electrical conductivity.

This welding may, and preferably is, accomplished by the arc-method with added metal. For the sake of clearness in illustrating the elements, I have not shown the added metal but the 25 same will be readily understood by those having practical acquaintance with the art.

It will be noted that the two wings 6 and 7 are of substantially the same area and have corresponding edges 9 and 10 of substantially 30 equal length, so that, when the edges 9 and 10 of the wing 6 or the wing 7, whichever happens to be located above rail, are welded to the rail base, the terminal is attached to the rail with equal rigidity and permanence.

35 In attaching the terminals 5 to the ends of the conductor 4 I prefer to cut the end of the conductor off square and clamp around said end a strip of metal 11, similar to that of which the terminals are formed, whose opposite ends may 40 be formed with dovetail or complementary portions 12 and 13, which serve to hold the ends of the strip together when the strip is bent up and clamped about the end of the conductor 4, as illustrated in dotted lines in Fig. 5. When the 45 sleeve 11 is thus clamped about the end of the conductor, the end of the conductor and the outer end of the sleeve are substantially flush.

Turning now to the terminals 5, it will be noted that each is provided with a boss 14 of 50 cylindraceous shape cast or otherwise formed integral with the inner end portion of one of the wings, such as 6, the boss being cylindraceous for a portion thereof and then tapering into and merging with the surface of the side and presenting at the inner end of the terminal a flat 55 substantially circular surface against which, in manufacturing the bond, the sleeved end of the conductor 4 and the end of the encircling metal sleeve are snugly held and butt-welded permanently in place. The welding edge 9 of the side of the terminal which carries the boss 14 extends only part way along the terminal, terminating substantially at the end of the boss.

To provide clearance for conveniently welding the edge 9 of the wing 6 to the rail base when the terminal is in the position shown in Fig. 1, the inner end of the boss 14 merges in an arcuate and inclined manner into the outer face of said 5 wing.

If desired, any other convenient method of attaching the ends of the conductor 4 to the terminals 5 may be employed, many types of such attachments being known and illustrated in the 10 prior art, but I prefer the type of attachment above described.

I claim:—

1. A rail bond terminal which is reversible on the rail flange whereby to place the bond conductor either above or below the flange as may be desired, comprising a member of substantially U-shaped cross section with two diverging sides, and means for connecting the conductor to one of said sides, each side being provided with a 20 substantially straight edged surface longitudinally of the rail flange for welding the terminal to said flange.

2. A rail bond terminal which is reversible on the rail flange whereby to place the bond conductor either above or below the flange as may be 25 desired, comprising a member of substantially U-shaped cross section with two diverging sides, an integral boss at one end of one of said sides 30 for connecting a conductor thereto, said boss being cylindraceous for a portion thereof and then tapering into and merging with the surface of said side, and a welding edge surface on each side extending longitudinally of said terminal 35 and on one side between the end of the taper of said boss and the other end of said side.

3. A rail bond terminal which is reversible on the rail flange whereby to place the bond conductor either above or below the flange as may be 40 desired, comprising a member of substantially U-shaped cross section with two diverging sides which are symmetrical in respect to a plane bisecting their included angle, and means for connecting a conductor to one of said sides, said sides 45 being provided with substantially straight edges longitudinal of the rail for welding to the rail flange.

4. A rail bond terminal which is reversible on the rail flange whereby to place the bond conductor either above or below the flange as may be 50 desired, comprising a member of substantially U-shaped cross section with two diverging sides which are symmetrical in respect to a plane bisecting their included angle, and means for connecting a conductor to one of said sides, said sides being provided with substantially straight edges longitudinal of the rail for welding to the rail flange, the angle between said diverging sides being less than the angle between the surfaces of the rail flange to permit the bond terminal to fit snugly on the rail flange when in either of its reversed positions.

NORTH C. SHAVER.
